WATER SKI

Johnny L. Hughes, Lancaster, Calif. (4745 W. K-10, Quartz Hill, Calif. 93534), and Ross A. Rhodes, Riviera, Ariz. (P.O. Box 40, Greenfield, Okla. 73043)

Filed Apr. 8, 1974, Ser. No. 458,771

Term of patent 14 years

Int. Cl. D21—02

U.S. Cl. D34—40

Fig. 1

Fig. 2

Fig. 3

Fig. 4

Fig. 5

Fig. 6

FIG. 1 is an elevation view showing one side of a water ski showing our new design, the opposite side having the same appearance;

FIG. 2 is a view showing the top thereof as seen from the lines 2—2 of FIG. 1;

FIG. 3 is a view showing the rear thereof as seen from the lines 3—3 of FIG. 2;

FIG. 4 is a view showing the front thereof as seen from the lines 4—4 of FIG. 2;

FIG. 5 is a view showing the bottom thereof as seen from the lines 5—5 of FIG. 1; and

FIG. 6 is a perspective view thereof.

We claim:

The ornamental design for a water ski, substantially as shown and described.
